UNITED STATES PATENT OFFICE.

WILLIAM J. McNAMARA, OF CLEVELAND, OHIO, ASSIGNOR TO EMPIRE PHONO PARTS COMPANY, OF CLEVELAND, OHIO, A CORPORATION OF OHIO.

DESIGN FOR A TONE-ARM.

53,456.

Specification for Design.

Patented June 17, 1919.

Application filed April 4, 1919. Serial No. 287,626. Term of patent 14 years.

To all whom it may concern:

Be it known that I, WILLIAM J. McNAMARA, a citizen of the United States, residing at Cleveland, in the county of Cuyahoga and State of Ohio, have invented a new, original, and ornamental Design for Tone-Arms, of which the following is a specification, reference being had to the accompanying drawing, forming part thereof, and in which—

Figure 1 is a plan view, and Fig. 2 a side elevation of a tone arm embodying my new design.

I claim:

The ornamental design for a tone arm, as shown.

WILLIAM J. McNAMARA.
